US0D1020663S

(12) **United States Design Patent** (10) **Patent No.:** **US D1,020,663 S**
(45) **Date of Patent:** ** *Apr. 2, 2024

(54) **KEYPAD**

(71) Applicant: **Crestron Electronics, Inc.**, Rockleigh, NJ (US)

(72) Inventors: **Sae Jhun**, Bayside, NY (US); **Agnieszka Libson**, River Edge, NJ (US); **Benjamin Slivka**, Hillsdale, NJ (US); **Stan Wisniewski**, Pompton Plains, NJ (US)

(73) Assignee: **Crestron Electronics, Inc.**, Rockleigh, NJ (US)

(*) Notice: This patent is subject to a terminal disclaimer.

(**) Term: **15 Years**

(21) Appl. No.: **29/852,823**

(22) Filed: **Sep. 9, 2022**

(51) LOC (14) Cl. **13-03**

(52) U.S. Cl.

USPC **D13/162; D13/174**

(57) **CLAIM**

The ornamental design for a keypad, as shown and described.

DESCRIPTION

FIG. 1 shows a top front perspective view of a keypad.

FIG. 2 shows a bottom front perspective view thereof.

FIG. 3 shows a front view thereof.

FIG. 4 shows a right side view thereof.

FIG. 5 shows a left side view thereof.

FIG. 6 shows a top view thereof; and,

FIG. 7 shows a bottom view thereof.

The broken lines in the figures depict portions of the keypad that form no part of the claimed design.

1 Claim, 5 Drawing Sheets
